CLAIM

The ornamental design for a blow molded shelf as shown and described.

DESCRIPTION

FIG. 1 is a top front right perspective view of the blow molded shelf of the present invention;

FIG. 2 is a bottom rear left view thereof;

FIG. 3 is a top view thereof;

FIG. 4 is a bottom view thereof;

FIG. 5 is a front view thereof;

FIG. 6 is a rear view thereof;

FIG. 7 is a left side view thereof; and,

FIG. 8 is a right side view thereof.

The portions of the figures illustrated in broken lines form no part of the claimed design for the blow molded shelf.

1 Claim, 6 Drawing Sheets(56)
